WINDOW

Boyd A. Stere and Elmer C. Ausnehmer,
Youngstown, Ohio

Application August 28, 1933, Serial No. 687,120

3 Claims. (Cl. 189—66)

This invention relates to window frames and sashes.

More especially this invention pertains to a window frame having a pair of vertically sliding sashes together with a casement window for each sash. A window of this type has advantages over other types of windows such as ease in cleaning, full opening, and the choice of opening any part of the window to any desired degree, 10 together with a neat appearance.

We are aware that windows of this type have already been invented. This invention is an improvement over our patent on Window of August 15, 1933, Patent No. 1,922,505.

15 One of the principal objects of this invention is to provide more simplified, yet efficient windows of this type.

A further object of this invention is to provide a metal frame fitted with weather sealed sliding 20 metal sashes, each of these sliding metal sashes provided with a casement sash hinged thereto and constructed so as to form an efficient weather seal when in a closed position.

25 A further object of the invention is to provide oppositely disposed flanges along the vertical edges of the sashes together with oppositely disposed channels to which the oppositely disposed flanges slide.

30 A further object is to provide a weather seal for the lower edge of the lower sash together with a weather seal for the upper edge of the upper sash.

It is also pointed out that the structure of this 35 window provides for a pair of slideable sashes with casement sashes hinged thereto and mounted in such a manner that it is possible to open both casement sashes at the same time and in addition to that allowing for the movement of the slideable sashes up and down the frame so that the upper 40 slideable sash may be moved to the lower part of the frame while the lower slideable sash may be moved to the upper part of the frame in order to provide easy and convenient means for cleaning the windows.

45 A still further object is to provide a window comprising a window frame having a pair of slideable sashes and a pair of casement sashes contained therein, these sashes counterbalanced so that the necessity for sash weights ordinarily used is eliminated. Another advantage of a 50 window of this type is in providing means for placing a number of windows in close relation to each other through the elimination of space ordinarily necessary for the weights.

55 With the foregoing and other objects in view

which will appear as the description proceeds, the invention resides in the combination and arrangement of parts and in the details of construction hereinafter described and claimed, it being understood that changes in the precise 5 embodiment of the invention herein disclosed, can be made within the scope of what is claimed, without departing from the spirit of the invention.

The invention is illustrated in the accompanying 10 drawings, wherein:—

Figure 1 is a front elevation of the device.

Figure 2 is an enlarged cross section taken on line 2—2 of Figure 1.

Figure 3 is a perspective view showing a cross 15 section through the frame of the window so as to disclose an outer edge of the upper and lower slideable sashes.

Figure 4 is an enlarged cross section taken on line 4—4 of Figure 1. 20

Figure 5 is an enlarged detail view of a weather seal strip.

Figure 6 is a detail view of Figure 4 showing an enlarged portion of a glass securing strip.

Figure 7 is a perspective view of the upper slideable sash with casement window in an open position. 25

By referring to the drawings it will be seen that there is provided a metal window frame 1. Slidably maintained within this window frame 1 30 there is an upper slideable sash 2 and a lower slideable sash 3. By referring to Figure 2 it will be seen that these sashes 2 and 3 are held in slideable relation to the frame 1 by means of a blind stop 4, a window stop 5, and a parting strip 6, all of 35 which are held in position by means of screws 7. It will be seen that the vertical edges of the slideable sashes 2 and 3 are provided with oppositely disposed flanges 8 and 9. The inner flanges 9 are each slidably maintained within a channel 40 formed by the T-shaped parting strip 6 and the frame 1, and the flanges 8 are slidably maintained within channels formed by projections 10 of the blind stop 4 and the window stop 5, together with the window frame 1. It will be seen that the 45 inner side of the frame 1 is provided with a window trim 11.

By referring to Figure 4 it will be seen that the upper horizontal part of the frame 1 is provided with a fillet stop 12 which is provided with downwardly extended portions 13 and 14, thus forming a recess into which fits the upper edge of the upper sash 2. It will be seen that this upper edge of the sash 2 is provided with a semi-circular 50 channel 15, thereby forming window sealing pro- 55

jections 16. It will also be seen that the sashes 2 and 3 are formed with flanges 17 at right angles to inner edges 18. It will be seen that in the inner corners of the angles formed by the flanges 17 and inner edges 18, there is provided a weather channel 19. It will be seen that the lower horizontal portion of the upper sash 2 is provided with an outwardly extending flange 20 to which is secured a meeting rail 21. This meeting rail 21 is provided with an angular notch 22 into which fits an outwardly extending horizontal flange 23 formed on the upper edge of the lower sash 3. It will be seen by referring to Figures 4 and 5 that there is provided a weather drain and seal 24 which is semi-circular in form and which is attached to a window sill 25. The lower edge of the lower sash 3 is provided with a semi-circular recess which fits over the window drain and seal 24 when the lower sash 3 is in a closed position. This weather drain and seal 24 is provided with an upper drain channel 26 and lower drain channels 27. The lower drain channels 27 are connected by transverse channels 28. It will also be seen that there is attached to the sill 25 a window stool 29 and an apron 30.

By referring to Figures 2, 4, and 7 it will be seen that there is provided hinged casement sashes 31 hinged to the sashes 2 and 3 by means of hinges 34. These hinged casement sashes 31 are essentially formed of angle material and are each provided with an outwardly extending weather seal flange 32 which covers the inner perimeter of the flange 17. It will also be seen that at the outer corners of the hinged casement sashes 31 and adjacent to the weather channel 19 there is provided a drainage channel 33. It will also be seen that a glass 35 for each of the casement sashes 31 is held in position by means of a glass securing strip 36 provided with a relatively short rib 37 and an inturned flange 38. This glass securing strip 36 is held in position by means of screws 39.

By referring to Figure 3 it will be seen that the upper sash 2 and the lower sash 3 are counterbalanced by means of a cord 40 which passes over a pulley 41. One end 42 of this cord 40 is attached to the upper sash 2 and the other end 43 is attached to the lower sash 3. It will be noticed that semi-circular recesses 44 in the vertical edges of the sashes 2 and 3 provide space for the carrying of the cord 40. In the construction of buildings using a plurality of windows adjacent to each other space can be saved between the windows by using this particular construction.

By referring to Figure 1 it will be seen that there is provided latches 45 for the purpose of latching the casement sashes 31. It will also be seen that there is provided a second latch 46 for the purpose of holding the upper sash 2 and the lower sash 3 in a locked position when closed.

What we claim is:—

1. In a window construction comprising a frame, slidable sashes maintained within said frame and casement sashes hinged to said slidable sashes, said sashes formed of angle material and

an outwardly extending weather seal flange formed on each of said casement sashes, oppositely disposed flanges on said slidable sashes, a detachable T-shaped parting strip functioning with said slidable sashes, detachable blind stops secured to said window frame, in-turned projections on said blind stops forming a channel in connection with the frame for said oppositely disposed flanges, a meeting rail secured to a lower horizontal portion of the upper sash, said meeting rail provided with an angular notch, a horizontal flange formed on the upper edge of the lower sash and fitting into said angular notch for the purpose of weather sealing the two sashes when in a closed position. 15

2. In a window construction comprising a frame, slidable sashes maintained within said frame and casement sashes hinged to said slidable sashes, said sashes formed of angle material and an outwardly extending weather seal flange 20 formed on each of said casement sashes, oppositely disposed flanges on said slidable sashes, a detachable T-shaped parting strip functioning with said slidable sashes, detachable blind stops secured to said window frame, in-turned projections on said blind stops forming a channel in connection with the frame for said oppositely disposed flanges, a meeting rail secured to a lower horizontal portion of the upper sash, said meeting rail provided with an angular notch, a horizontal flange 25 formed on the upper edge of the lower sash and fitting into said angular notch for the purpose of weather sealing the two sashes when in a closed position, a semi-circular recess formed in lower edge of the lower sash, a semi-circular 30 weather drain and seal secured to the window sill and fitting into the semi-circular recess when the sash is in a closed position.

3. In a window construction comprising a frame, slidable sashes maintained within said 40 frame, casement sashes hinged to said slidable sashes, said sashes formed of angle material and an outwardly extending weather seal flange formed on each of said casement sashes, oppositely disposed flanges on said slidable sashes, 45 a detachable T-shaped parting strip functioning with said slidable sashes, detachable blind stops secured to said window frame, in-turned projections on said blind stops forming a channel in connection with the frame for said oppositely disposed flanges, means for weather sealing said casement sashes when in a closed position, a meeting rail secured to a lower horizontal portion of the upper sash, said meeting rail provided with an angular notch, a horizontal flange 50 formed on the upper edge of the lower sash and fitting into said angular notch for the purpose of weather sealing the two sashes when in a closed position, a semi-circular recess formed in lower edge of the lower sash, a semi-circular weather drain and 55 seal secured to the window sill and fitting into the semi-circular recess when the sash is in a closed position.
